Specification of Letters Patent.

Patented Jan. 4, 1921.

Application filed August 2, 1919. Serial No. 314,878.

To all whom it may concern:

Be it known that I, HAROLD E. HOUSEMAN, a citizen of the United States, residing at Philadelphia, county of Philadelphia, 5 and State of Pennsylvania, have invented a new and useful Improvement in Safety Stopping Devices for Circular-Knitting Machines, of which the following is a full, clear, and exact description, reference being 10 had to the accompanying drawings, which form a part of this specification.

In the modern automatic circular hosiery knitting machine, it is customary to provide a pattern chain which controls the operation 15 of a pattern disk or cylinder, the latter carrying parts which control the operation of various elements of the machine, such as the clutch for shifting from rotation to oscillation and vice versa, the cams for raising half 20 the needles out of action and restoring them to action, the cams for rendering active the lifting pickers and lowering pickers, the means for shifting yarn changing fingers into and out of action, etc. To enable the 25 pattern chain to control the pattern disk or cylinder, the chain is provided at suitable intervals with lugs or high links, which control the operation of mechanism for turning the pattern disk or cylinder. The 30 pattern disk or cylinder dictates certain operations of the machine in a certain sequence, but the time elapsing between certain of these various operations of the machine may be varied by using chains of different 35 length and regulating the distance, measured in links, between the lugs. In any pattern chain, however, the distances between lugs are necessarily quite variable, and therefore it is of vital importance that a given pattern 40 lug on the chain shall turn the pattern disk or cylinder to the position required to effect the operation of a given element or series of elements. Inasmuch as it is necessary, at the beginning of a stocking, that 45 the pattern disk or cylinder shall be brought to a certain position, the pattern chain must be brought to a synchronous position. If proper care be exercised by a properly instructed operative, no trouble can arise; but 50 unfortunately, due to ignorance or carelessness on the part of an operative, the chain is not always positioned to synchronize with the pattern disk. This condition may arise, for example, if, for any reason, the machine

has been stopped and the chain shifted and 55 then has not been restored to proper position; the consequences then, after the machine is re-started, often being quite serious, in that needles are broken and parts of the machine are damaged or ruined. The most 60 vital damage is apt to occur as the machine goes off the heel or toe.

For example, in a typical knitting machine, at the beginning of the heel or toe, the clutch is shifted to cause the machine 65 to change from rotation to oscillation, half the needles are moved out of action, the yarn changing fingers are operated, and the pickers start to lift the remaining needles out of action one by one. After the heel or toe is 70 half knit, the lowering pickers are rendered active. At the conclusion of the heel or toe knitting, the clutch is again shifted, all the pickers are rendered inactive, the bank of needles that was moved out of action at the 75 beginning of the heel or toe is moved into action and the yarn changing fingers are operated. These described operations require three shifts of the pattern disk or cylinder, which are caused to be effected by 80 three lugs on the pattern chain. It is obvious that these three lugs must be spaced a given distance apart, because the chain moves synchronously with the needle cylinder, and just as the needle cylinder must 85 oscillate a given number of times to complete the heel and toe, so must the chain move a given number of links during the same period. If the lugs are not properly spaced, then the last two of said three shifts 90 of the pattern disk or cylinder will be made when the needles and other elements are not in proper position for the operations mentioned.

Assuming an improper spacing of the lugs 95 on the pattern chain, it is impracticable to specify exactly just what the abnormal conditions would be when the moment arrives for going off the heel or toe, as these conditions will be different on machines of different make, and will, indeed, vary on the same machine. On "Standard" or "Houseman" machines (see, for example, Houseman Patent No. 1,207,757, dated December 12, 1916), the needles would be in such position 100 that they would afford no space for the necessary movement of the cam that restores the inactive half of the needles to action and no

room for the yarn changing fingers to go into and out of action. These parts would necessarily, however, positively operate, and would break a number of needles and break 5 or bend any parts whose positive movements would be obstructed and any parts obstructing the movement of the positively actuated parts.

It is clear, therefore, that if the chain is 10 in such position that the wrong lug on the pattern chain effects that shift of the pattern disk or lug which causes the machine to start to knit the heel or toe, the fact that the two lugs following it will not be spaced 15 therefrom at distances corresponding to the spacing of the two lugs following the proper lug, will produce abnormal conditions of which these alluded to are illustrative.

It will be understood that I have simply 20 cited a typical case, the possibilities of grave injuries to machine parts not being necessarily confined to that stage of the knitting at which the heel or toe is completed.

The object of my invention is to safeguard 25 against accidents of this character.

I have accomplished this result by causing the machine to be stopped automatically, before any damage can be done, in case the pattern chain is not properly adjusted to 30 correspond with the position of the pattern disk or cylinder. I have illustrated one embodiment of my invention which has been carefully worked out mechanically and the operativeness of which has been demonstrated by prolonged experimental and practical use. I have also illustrated other embodiments of the invention, which illustrate rational embodiments of the same inventive conception. Other embodiments, with the 35 suggestions afforded by the structures shown and described, could readily be worked out by the skilled mechanic.

Figure 1 is a plan view of the machine, with the top of the machine table broken 40 away.

Fig. 2 is a partial front view of the mechanism shown in Fig. 1.

Fig. 3 is a rear view of the same.

Fig. 4 is a horizontal section on line 4—4 50 of Fig. 3.

Fig. 5 is an elevation of the machine, looking at the right hand side of Fig. 1.

Figs. 6 and 7 are side views of parts of the machine in different positions.

55 Figs. 8, 9 and 10 are views, similar to Figs. 6 and 7, of modifications.

Fig. 11 is a perspective view of a part of the pattern chain.

The driving shaft *a*, through bevel gears 60 *b*, *b'*, and spur gear *c*, drives a rotary pinion *e* loose on the shaft *d*, from which the needle cylinder is operated by the usual means (not shown). An oscillatory pinion *f*, loose on the shaft *d*, is actuated by an 65 oscillating quadrant *f'*. The quadrant is

carried on one end of a bell crank lever *f*² having rollers coöoperating with cams *f*³, *f*⁴, on the shaft *f*⁵ carrying gear wheel *b'*, *c*, as disclosed more specifically in the patent issued to me December 24, 1918, No. 1,288,594. A clutch *g*, feathered on the shaft *d*, is shifted by mechanism herein-after described, into engagement with the two pinions *e* and *f* alternately, thereby imparting to the needle cylinder alternate movements of rotation and oscillation. The clutch *g* is carried by an arm on a frame *h* 70 slidable vertically on a post *j*.

The pattern disk *i* is provided with peripheral ratchet teeth engaged by a pawl 80 *m*. The pawl *m* is operated at suitable intervals by mechanism controlled by the pattern chain, thereby turning the pattern disk *i* step by step. In some machines a pattern cylinder is used in place of a "disk," and it will be understood that the term "pattern disk," as used in this description and in the claims, is intended to include any device or apparatus that controls or effects the operation of the machine elements, such as, for 85 example, a pattern cylinder, a pattern drum, a pattern shaft, or a supplementary pattern chain. In the present machine, the pattern disk carries various devices which, as the disk is turned at irregular but fixed intervals, are moved successively into operation, these devices in turn actuating, or controlling the actuation of the various machine elements that control the knitting operation.

For example, a cam-way *k* on the periphery of the pattern disk operates, at a predetermined time, a pin *l* carried by the frame *h* thereby shifting the clutch *g* as hereinbefore described.

The pawl *m* is carried on a lever *n* extending from a hub *o* turnable on a post. The hub *o* has also arms *p* and *q*. The arm *q* carries a roller *r* engaging a cam *s* on the shaft *f*⁵, which, as before described, is constantly rotated. The cam *s* moves the arm *q* outwardly from the axis of the shaft *f*⁵, while a spring *s'* (when free to act) moves the arm *q* inwardly toward the axis of the cam. In the absence of other mechanism, therefore, the pawl *m* would be reciprocated at each rotation of the cam *s* and the pattern disk would be actuated at frequent and regular intervals. However, whenever the arm *q* is moved outward by the cam *s* (thus advancing the pawl *m* to advance the pattern disk *i*), the lever *p* engages and displaces the hooked end of one arm of a bell crank lever *t* (see Fig. 5), the latter being immediately returned to normal position by a spring *u*, thereby causing its hooked end to drop back of the lever *p* and prevent its return by the spring *s'*. The pawl *m* therefore is not retracted to engage the next tooth of the pattern disk ratchet until the lever *t* is moved to withdrawn its hooked end from 100 105 110 115 120 125 130

back of the lever *p*. This actuation of lever *t* is effected by the pattern chain, as hereinafter described.

The pattern chain 12 is actuated by the following mechanism: On the rotating shaft *r* is a cam *v* embraced by the bifurcated end of an arm *w* on a hub *x*, pivoted on the same post on which hub *o* is pivoted. The hub *x* has an arm *y* that carries a pawl *z* engaging a ratchet 10. The ratchet 10 is sleeved on the outside of the bearing for shaft *a* and carries a sprocket wheel 11. The pattern chain 12 extends around the wheel 11 and is advanced thereby, a distance 15 of one third of a link, at each reciprocation of the pawl *z*.

The pattern chain carries a series of lugs or high links. All of these lugs are adapted to actuate the lever *t*. One or more of these 20 lugs (13) project laterally from the pattern chain, as shown in Fig. 3, and are adapted to operate other mechanism, as hereinafter described. When any lug underrides the end of the lever *t* adjoining the chain, it lifts the 25 lever so as to disengage its hooked end from the lever *p*, allowing the spring *s*' to draw the arm *q* against the low face of the cam *s*, which then swings the lever *q* so as to advance the pawl *m* and ratchet the pattern 30 disk *i* forward a distance of one tooth.

To the mechanism above described, I have applied my safety contrivance. While the safety contrivance may be embodied, as before stated, in different forms, I prefer to so 35 design and apply it that it will operate if one of the regular lugs 14 (in the specific embodiments shown herein any of the narrow lugs) underrides the lever *t* at one or more stages of the knitting operation, but so 40 that it will be withheld from operation if a special lug (in the present case a lug 13) underrides the lever *t*. It is obvious that if this special lug is the one which, when the chain is properly positioned, is intended 45 to effect the operation of the pattern disk so as to dictate the operation of elements which are designed to operate at such stage of the knitting operation, the safety contrivance will not operate and hence the machine will operate just as if it were equipped 50 with no safety device whatever.

Bearing in mind that disastrous results are to be apprehended only after the machine passes onto the heel or toe, I have, in 55 my preferred embodiment, so arranged the safety contrivance that it will be adapted to operate only as the machine passes onto the heel or toe. The chain is provided with two of the special lugs 13, each of which 60 (when the pattern chain and pattern disk are properly synchronized) effects that actuation of the elements designed to be operated at these two stages of the knitting operation. It is therefore clear that if the 65 pattern chain and pattern disk be properly

synchronized, the safety contrivance will never operate, but that if the pattern chain and pattern disk are not properly synchronized, so that one of the lugs 14 actuates the pattern disk to cause the machine to pass 70 onto the heel or toe, the safety contrivance will operate.

Having now explained the characteristic intended mode of operation of the preferred embodiment of my invention, I shall explain 75 the construction and operation of the specific safety device which I have actually used and which is illustrated in Figs. 1 to 7 inclusive.

On the driving shaft *a* is the fixed pulley 15 and the loose pulley 16. (See particularly Figs. 1 and 2.) 17 is a belt shifter 80 slidable on a guide rod 18. A spring 19 (Figs. 1 and 4) tends to actuate the belt shifter to shift the belt from the fixed pulley 15 to the loose pulley 16. A stop 20 normally prevents the belt shifter from so moving. A spring-pressed rock-arm 21, to which the stop 20 is secured, normally holds the stop in operative position.

The clutch-carrying frame *h* has bearings 90 in which is swiveled a rod 23, to which is secured an arm 22, which loosely embraces a pin 200, secured to the lever 21. In the normal operation of the machine, the rod 23 does not turn, its only movement being an 95 up and down movement, with the clutch frame, when the clutch *g* is shifted. This up and down movement does not actuate the stop 20, the arm 22 merely sliding up and down on the pin 200.

The rod 23 has at its upper end a head to which a pin 24 is secured. 25 is a lever pivoted between its ends. One end of this lever extends alongside of the chain-operated end of lever *t* in position to be engaged by one of the special lugs 13 but not in position to be engaged by one of the regular lugs 14. A spring 27 holds the lever 25 in the path of travel of the lugs 13. The other end of lever 25 is shaped to provide a recess 26 normally in line of the downward movement of the pin 24, as shown in Fig. 5.

It will be clear that if a wrong lug 14 actuates the lever *t* when the pattern disk 115 *i* is in position to shift to dictate the beginning of heel or toe knitting, the lever 25 will not be actuated. Consequently, in the lowering of the clutch *g* (which is one of the operations at this stage of the knitting), 120 the pin 24 moves into the recess 26 and pushes down the corresponding end of the lever 25. The lever 25 is so pivoted that, as its recessed end moves down with the clutch frame *h*, it necessarily has also a 125 lateral movement relatively thereto, causing it, by reason of its engagement with the pin 24, to move the pin laterally and thereby turn the rod 23 on its axis, as shown in Fig. 6. The turning of rod 23 swings the 130

arm 22, which withdraws the stop 20 out of operative position, and the belt shifter 17 is immediately actuated by the spring 19 to shift the belt from the tight pulley 15 to 5 the loose pulley 16, thereby stopping the machine.

Suppose, however, that a correct lug 13 actuates the lever *t* when the pattern disk is in position to shift to dictate the beginning 10 of the heel or toe knitting. Then the lever 25 will be operated by the lug slightly before the lug operates the lever *t*, although (in the specific embodiment shown) in the same turn of the sprocket wheel 11, and the 15 recessed end of the lever will swing into the position shown in Fig. 7, moving this end of the lever below, or out of the path of travel of, the pin 24. Hence, when the pattern disk *i* is turned and the clutch frame *h* moves down, the pin 24 will not coat with 20 the recess 26 and the belt shifting mechanism will not operate.

The coaction between lever 25 and pin 24 in the specific construction described involves 25 an operation of each by the other. In Fig. 8 is shown a slight modification. Here the lever 30 (corresponding to lever 25) is held in position to be operated by a lug 13 by means of a spring 31. Spring 31 corresponds to spring 27 but should be of 30 greater strength. The actuating end of lever 30 is provided with an upturned edge the inner wall of which forms a cam 32 in line of movement of the pin 24. If, preparatory 35 to that shift of the pattern disk *i* which dictates the beginning of heel or toe knitting, the proper lug operates the lever 30, the lever 30 is swung out of the path of movement of the pin 24, but if a wrong lug 40 operates the lever *t*, thereby leaving the lever 30 in its normal position, the pin 24, in the lowering movement of the clutch frame, rides upon the cam 32 and is turned on its axis, thereby causing the belt-shifting mechanism 45 to operate.

In the foregoing construction the pattern chain controls the position of the lever 25 or 50 30 and the stop mechanism is operated by the movement of the clutch shifter. In the construction shown in Fig. 9, the pattern chain, as before, controls the position of the lever, but the stop mechanism is actuated by the pattern disk *i*. The lever 40 (corresponding to lever 25 or 30) has a slot 41 en- 55 gaging a pin 42. The lever 40 is therefore both turnable and slidable on the pin 42. A spring 43 holds the lever in its left-hand position, in which position it is in operative relation with the pattern chain. A stop 44 60 prevents the lever 40 turning on its axis except in opposition to the spring 43. The actuating end of lever 40 has a cam-actuated head 45 provided with an actuating cam 46. The head 45 is normally in line of travel of 65 a cam 47 on the pattern disk *i*. When the

cam 47 engages the head 45 it tilts the corresponding end of the lever 40 down, thus causing the cam 46 to engage the pin 24 and thereby swing the rod 23 to actuate the belt-shifting mechanism. This operation will occur only if the wrong pattern chain lug operates the lever *t*, thereby leaving lever 40 in position to be operated, as described, by the cam 47. But if the correct lug operates lever *t*, it also operates lever 40, sliding it 70 to the right so that, when depressed by the cam 47, it moves back of the pin 24, which is not then operated. The advantage of this construction is that the cam 47 can be positioned at any point on the periphery of the 80 pattern disk, so that the safety contrivance may be made to operate at any stage of the knitting operation. It should be mentioned that, in this modification, the turnable rod 23 is not carried on the clutch-shifting 85 frame, but is journaled on a fixed part of the machine frame. In the drawings, the rod is shown as turnable in two fixed supports 48.

In the construction shown in Fig. 10, the lever 50 (corresponding to lever 25, 30 or 40) is operated to actuate the stop mechanism by the pattern chain itself. One end of the lever 50 is held into operative relation with the chain by a spring 51 and is 95 pivoted at 52. The other end of the lever 50 has a cam 53 adapted, when depressed, to engage the pin 24 and turn the rod 23 to stop the machine, as before described. This operation will occur as soon as a special lug 13 100 engages the lever 50, unless the pattern disk is properly positioned relatively to the pattern chain; but if the disk is in its proper position relative to the chain a stop 54 carried by the disk underlies a projection 55 105 on the lever 50 and prevents the lever 50 from being tilted by the pattern chain lug. To allow the actuated end of the lever 50 to move up without moving down its opposite end, the first named end is jointed at 56. A 110 stiff spring 57 holds the jointed members of lever 50 in normal relative position unless the actuating end of lever 50 is positively withheld from moving down by the positive stop 54.

Having now fully described my invention, what I claim and desire to protect by Letters Patent is:

1. In a circular knitting machine, the combination with driving means, of a clutch, a 120 pattern disk and actuating means therefor, a cam on the pattern disk for controlling the action of the clutch, a pattern chain, lugs irregularly spaced on the pattern chain and adapted to render said actuating means 125 operative and thereby impart intermittent movements to the pattern disk at irregular intervals; of mechanism to stop the machine, and contrivances adapted to effect the operation of the stop mechanism and in 130

operative relation with both the pattern disk and one of said lugs on the pattern chain and adapted to be rendered operative or inoperative to stop the machine dependent upon the position of the clutch cam on the pattern disk when said last mentioned lug is rendered operative in the movement of the pattern chain.

2. In a circular knitting machine, the combination with driving means, of a pattern disk, and actuating means therefor, mechanism to stop the machine, a contrivance controlling the operation of the stop mechanism, and a pattern chain comprising lugs of differential characteristics all of which are adapted to render said pattern disk actuating means intermittently operative, while one of said lugs is also adapted to operate said contrivance and thereby cause the stop mechanism to be operated or not dependent upon whether the pattern chain is or is not out of synchronous relation with the pattern disk.

3. In a circular knitting machine, the combination with driving means including a reciprocable clutch adapted to cause a part of said driving means to either rotate or oscillate, a pattern disk adapted, at predetermined but irregular intervals, to control the proper operation of the knitting mechanism and said clutch, through the medium of the clutch pattern disk actuating means, and a pattern chain adapted, when properly synchronized with the pattern disk, to so control the operation of said actuating means as to effect the specified operation of the pattern disk; of mechanism to stop the machine, a clutch frame carrying said clutch, contrivances adapted to cooperate with the clutch frame to effect the operation of the stop mechanism, and means adapted, when the chain is properly synchronized with the pattern disk, to prevent said coöperation of said clutch frame and contrivances.

4. In a circular knitting machine, the combination with driving means including a reciprocable clutch adapted to cause a part of the driving means to either rotate or oscillate, a pattern disk adapted to control

the operation of the knitting mechanism, actuating means for the pattern disk, a pattern chain adapted to control the operation of said pattern disk, mechanism to stop the machine, and a clutch frame carrying said clutch, of means controlled by the pattern chain and adapted to render the clutch frame in its movement operative or inoperative to operate the stop mechanism dependent upon whether the pattern disk is or is not out of synchronous relation with the pattern chain.

5. In a circular knitting machine, the combination of driving means including a reciprocable clutch adapted to cause a part of the driving means to either rotate or oscillate, a pattern disk adapted to control the operation of the knitting mechanism, actuating means for the pattern disk, a pattern chain comprising lugs all of which are adapted to render said pattern disk actuating means intermittently operative, mechanism to stop the machine, a clutch frame carrying said clutch, means carried thereby adapted when the clutch is shifted to be turned into position to operate said stop mechanism, and a contrivance adapted to cause such turning movement of such clutch frame, one of said lugs also being adapted to shift said contrivance and thereby prevent such turning movement, whereby, if the clutch frame is shifted contemporaneously with the operation of said contrivance, the machine will not be stopped.

6. A circular knitting machine having oscillatory and rotary driving mechanism, clutch mechanism for connecting either of said mechanisms, clutch shifting mechanism including a pattern disk, means for intermittently actuating the pattern disk, a pattern chain for controlling the action of the pattern disk, and means to stop the machine operable if the clutch shifting mechanism and the pattern chain are out of timed relation.

In testimony of which invention, I have hereunto set my hand, at Philadelphia, Pa., on this 30th day of July, 1919.

HAROLD E. HOUSEMAN.
